UNITED STATES PATENT OFFICE.

JULIUS KOHN, OF BRIDGEPORT, CONNECTICUT.

AUTOMATIC STOP FOR TALKING-MACHINES.

1,107,079.

Specification of Letters Patent. Patented Aug. 11, 1914.

Application filed December 29, 1913. Serial No. 809,244.

To all whom it may concern:

Be it known that I, JULIUS KOHN, a subject of the King of Hungary, residing at Bridgeport, in the county of Fairfield and State of Connecticut, have invented certain new and useful Improvements in Automatic Stops for Talking-Machines, of which the following is a specification.

This invention relates to certain new and useful improvements in automatic stops for talking machines, and the object of the invention is to provide a brake and operating mechanism therefor which will be positive in all its actions, insuring its proper operation and the stopping of the record at the proper time.

It is a further object of the invention to provide such a device which will be simple in its construction and operation, which can be manufactured at a comparatively small cost, and which can be readily attached to any of the usual well known types of talking machines.

With the above and other objects in view, the invention resides in the novel construction, combination, and arrangement of parts as will be hereinafter more fully described and then claimed, and in describing the invention in detail, reference will be had to the accompanying drawing forming a part of this specification, and wherein like numerals of reference will be employed to designate like parts throughout the several views, in which:

Figure 1 is a top plan view of a talking machine or phonograph partly broken away showing my invention applied thereto. Fig. 2 is a top plan view of the brake mechanism on an enlarged scale, a portion of the phonograph box and record being shown. Fig. 3 is a view in side elevation of the brake and its operating mechanism, the supporting arm for the sound reproducer being in transverse section. Fig. 4 is an enlarged detail view of a portion of the brake mechanism partly in section, and Fig. 5 is a transverse vertical sectional view taken on the line 5—5 of Fig. 2 with part of the brake mechanism removed.

In the accompanying drawings I have illustrated the preferred embodiment of my invention, and have shown the same applied to a talking machine of a well known type, and comprising a motor casing 10 upon which, as is well known, is a rotatable support (not shown) which carries a central

pin 11 by which the record 12 is centered on such rotatable support. The sound reproducer 14 is carried on an arm 15 and is usually pivotally supported by a bracket 60 on one side of the motor casing. The parts thus far described are all of an ordinary and well known form.

The brake mechanism comprises a disk or plate 16 which is secured on top of the 65 motor casing 10 on the side adjacent to the pivoted end of the arm 15. This plate is preferably mounted on a cushion 17, usually made of rubber, the securing screws 18 extending through both the plate 16 and 70 the cushion 17 into the top of the motor casing 10. This cushion is of a thickness which will elevate the plate 16 to such a point as will permit the brake to engage the periphery of the record, as will herein- 75 after more fully appear.

Pivoted at 19 centrally of the plate or disk 16 is a lever 20, having a setting arm 21 at one end and a brake carrying arm 22 at the other end, both of these arms lying in planes 80 above the plane of the lever 20. The setting arm 21 is preferably provided on its free end with a button 23, this arm extending at right angles to the lever 20, while the arm 22 is provided near its free end with an aperture 85 through which extends a shaft or rod 24 carrying a brake 25 on its outer end. This rod or shaft 24 at its other end extends through a swiveled support 26 and surrounding the rod or shaft between said support 26 90 and the arm 22 is a coiled spring 27.

On the plate 16 is a pair of spaced standards or lugs 28 in which is pivotally mounted a latch 29 having at one end a hook 30 to engage with the lever 20 and with which it 95 is normally held in engagement by a spring 31. At its other end the latch 29 has an inclined surface 32 adapted to be engaged by a finger 33 clamped on the arm 15.

In operation, as the reproducer 14 approaches the end of the record, the movement of the arm 15 about its pivotal center will cause the finger 33 to engage and ride upon the inclined surface 32 of the latch 29, releasing the hook 30 from engagement with 100 the lever 20, allowing spring 27 to exert its tension against arm 22, which will cause the lever 20 to swing on its pivot 19 until the brake 25 is thrust against the periphery of the record 12, where it is held by the tension 105 of spring 27. To reset the device, it is merely necessary to press on button 23, which

again throws lever 20 underneath dog 30, spring 31 acting to engage the dog 30 with the lever 20 and hold the device in set position, or in other words, with the brake block 5 removed from the periphery of the record 12.

In order to impart the necessary movement to the parts quickly when the end of the record has been reached, I have shown 10 the record 12 as provided with a groove 34 extending inward from the end of the record, and described about a center other than the center of the record, thus causing the reproducing device and the arm to be carried inward quickly when the end of the record has 15 been reached.

While I have shown and described one form of my invention, it will be understood that this form has been chosen for the purpose of illustration only, and that I do not wish to be limited to the details and construction shown and described, as obvious modifications will occur to those skilled in the art.

25 Having thus fully described my invention, what I claim as new and desire to secure by Letters Patent is:—

1. In brake mechanism for talking machines, the combination with a rotating member and a traveling member, of a pivotally-mounted lever having a setting arm at one

end and a brake arm at its other end, a swiveled support, a rod extending through said support and through said brake-arm, a brake on one end of said rod, a spring surrounding the rod, a spring-controlled latch having a hook at one end adapted to engage said lever, and beveled at its opposite end, and a finger carried by said traveling member adapted to contact with the beveled end 40 of said latch to release the latter from said lever.

2. In brake mechanism for talking machines, the combination with a rotating member and a traveling member, of a pivotally-mounted lever provided at one end with a setting arm, and at its opposite end with a brake arm, a spring-pressed rod extending through said brake arm, a spring on said rod, a brake on one end of said rod, a spring-pressed latch having a hook at one end to engage said lever, and beveled at its opposite end, and a finger carried by said traveling member adapted to contact with the beveled end of said latch to release the latch from 55 said lever.

In testimony whereof I affix my signature in presence of two witnesses.

JULIUS KOHN.
